US00D895239S

(12) United States Design Patent (10) Patent No.: US D895,239 S
(45) Date of Patent: * Sep. 8, 2020

(54) SHOE

(71) Applicant: NIKE, Inc., Beaverton, OR (US)

(72) Inventors: Noah Murphy-Reinhertz, Portland, OR (US); Haley L. Toelle, Portland, OR (US); James Zormeir, Portland, OR (US)

(73) Assignee: NIKE, Inc., Beaverton, OR (US)

() Term: 15 Years

(21) Appl. No.: 29/694,987

(22) Filed: Jun. 14, 2019

(51) LOC (12) Cl. 02-04

(52) U.S. Cl.

USPC D2/947; D2/960

(58) Field of Classification Search

USPC ..... D2/902, 906, 908, 916, 918, 925, D2/946-962, 972, 977; 36/3 B, 22 R, 36/24.5, 25 R, 28, 32 R, 34 R, 59 C, 36/67 A, 103; D5/43, 44; D25/151 CPC A43B 13/00; A43B 13/02; A43B 13/023; A43B 13/026; A43B 13/04; A43B 13/08; A43B 13/10; A43B 13/12; A43B 13/14; A43B 13/141; A43B 13/143; A43B 13/16; A43B 13/18; A43B 13/181; A43B 13/187; A43B 13/189; A43B 13/20; A43B 13/22; A43B 13/223; A43B 13/24; A43B 13/28; A43B 13/30; A43B 13/32; A43B 13/34; A43B 13/36

(57) CLAIM

The ornamental design for a shoe, as shown and described.

DESCRIPTION

The patent or application file contains at least one drawing executed in color. Copies of this patent or patent application publication with color drawing(s) will be provided by the Office upon request and payment of the necessary fee. FIG. 1 is a rear perspective view of a shoe showing our new design;

FIG. 2 is a rear view thereof;

FIG. 3 is an opposite side rear perspective view thereof;

FIG. 4 is a rear perspective view of a shoe showing our new design in an alternate embodiment;

FIG. 5 is a rear view thereof;

FIG. 6 is an opposite side rear perspective view thereof;

FIG. 7 is a rear perspective view of a shoe showing our new design in an alternate embodiment;

FIG. 8 is a rear view thereof; and,

FIG. 9 is an opposite side rear perspective view thereof.

The broken lines immediately adjacent to the photographic area define the bounds of the claimed design and form no part thereof. The broken lines depicting the remainder of the shoe show features that form no part of the claimed design.

1 Claim, 9 Drawing Sheets
